UNITED STATES PATENT OFFICE.

ALFRED H. HUMPHREY AND HUBERT R. HUMPHREY, OF NEW YORK, N. Y.

GAS-LAMP.

No. 856,960.

Specification of Letters Patent.

Patented June 11, 1907.

Application filed June 22, 1906. Serial No. 322,890.

To all whom it may concern:

Be it known that we, ALFRED H. HUMPHREY and HUBERT R. HUMPHREY, citizens of the United States, residing at New York, county of New York and State of New York, have invented certain new and useful Improvements in Gas-Lamps, of which the following is a specification.

This invention relates to improvements in gas lamps.

The objects of this invention are, first, to provide an improved mantle support for gas lamps having a group of inverted burners by which the mantles are so supported as to be quickly and easily placed in position and are completely and conveniently accessible. Second, to provide an improved mantle support for inverted burners by which the mantles are so supported that the liability of injury in adjusting and arranging is reduced to a minimum. Third, to provide an improved mantle support for inverted burners by which the mantles are so held that they are not likely to be injured by the jarring of the lamp. Further object, and objects relating to structural details, will definitely appear from the detailed description to follow.

We accomplish the objects of our invention by the devices and means described in the following specification.

The invention is clearly defined and pointed out in the claims.

A structure embodying the features of our invention is clearly illustrated in the accompanying drawing forming a part of this specification, in which,

Figure 1 is a vertical section of a gas lamp embodying the features of our invention, taken on a line corresponding to line 1—1 of Fig. 2, portions being shown in full lines, and the globe being shown open and the mantle support lowered, by dotted lines. Fig. 2 is a horizontal section taken on a line corresponding to line 2—2 of Fig. 1, the mantle support being swung to one side. Fig. 3 is an enlarged perspective of the locking sleeve C.

In the drawing, the sectional views are taken looking in the direction of the little arrows at the ends of the section lines, and similar letters of reference refer to similar parts throughout the several views.

Referring to the drawing, in the structure illustrated the burners D are grouped about a chimney A, which is supported from the gas supply pipe F. The gas supply pipe F delivers to a ring E by which the burners are sup-

ported and through which the chimney A is arranged. On the lower end of the chimney A is an outwardly projecting flange A' having a downwardly turned rim A'' thereon. The inverted burners D are arranged through this flange A' as clearly appears in Fig. 1 of the drawing.

The plate-like mantle holder B is preferably arranged to fit quite closely within the downwardly projecting rim of the chimney flange. The mantle holder B is provided with openings adapted to receive the mantles G, the same being dropped through from the upper side. The mantles are preferably suspended from rings g, which fit into the openings in the holder and are provided with projecting ears or lugs g' which rest upon the same; see Fig. 2.

The holder B is carried by a rod B' which is adjustably arranged through the flange of the chimney and also through the flange h of the band H. The band H incloses the lower portion of the burners and forms the lower part of the lamp casing, the upper portion not being here illustrated. The rod B' is provided with a stop S which engages under the flange A' when the mantle support is in its adjusted position. On the upper end of the rod B' is a sleeve C having a longitudinal slot therein. The rod B' is also provided with a laterally projecting pin or finger piece b at its upper end which is engaged by the sleeve for holding the mantle support in position. The upper end of the sleeve is cam shaped or spiral so that by turning it under the pin b the supporting rod B' is drawn up until its stop S engages. The sleeve C is preferably provided with a finger piece C' for convenience in manipulating. To lower the mantle support to the position indicated by dotted lines in Fig. 1, the sleeve C is turned until the slot therein is under the pin b which permits the same to drop. It can then be swung out to one side as indicated in Fig. 2. It is evident that when in this position, the mantles can be easily inspected and renewed as desired. By this arrangement, the mantles are supported so that they are entirely accessible and are all adjusted in proper relation to the burner tips at the same time.

This adjusting may be done without liability of injury to the mantles. If it should be necessary to renew only one of the mantles, it can be done without danger to the other mantles.

The plate or holder B is preferably formed

of some material which is a non-conductor of heat, so that the heat is not carried away from the mantles, and so that it is not conveyed to the other parts of the lamp. It 5 also serves the purpose of a reflector, giving valuable results in this respect and adding to the attractive appearance of the lamp. We 10 preferably use magnesia and like materials for this purpose. In addition to the advantages mentioned, if carbon from the burners should be deposited thereon, it soon burns off and is not collected thereby, as is the case where the case is formed of brass or like metals.

15 As before stated, the support is held very firmly to the lamp so that the mantles are not likely to be injured by jarring or vibrations.

The globe is preferably supported by 20 securing the same to a ring I, which is pivoted at one side, as at J, so that it may be swung down as is indicated by dotted lines in Fig. 1. The globe is preferably held in its closed position by the thumb-screw K.

25 It is evident that our improved mantle support is very simple in its operation and that the mantle may be arranged very rapidly.

We have illustrated and described our improved mantle support in detail in the form preferred by us on account of structural simplicity and economy and convenience in use, although we are aware that it is capable of considerable variation in structural details 30 without departing from our invention.

35 Having thus described our invention, what we claim as new and desire to secure by Letters Patent is:

1. In a gas lamp, the combination of a 40 chimney having an outwardly and downwardly projecting flange at its lower end; a plurality of burners arranged in an inverted position through said flange; inverted mantles for said burners; a plate-like mantle holder having openings therethrough to receive the mantles and adapted to fit said flange on said chimney and substantially close the same, whereby the air is drawn toward the mantles by the draft of the chimney; an upwardly projecting supporting rod for said holder adjustably arranged through said flange on said chimney; a stop for limiting the upward movement of said rod; a locking sleeve having a longitudinal slot 45 therein arranged on said rod, the upper end of said sleeve being cam shaped; and a laterally projecting pin on said rod adapted to be engaged by said locking sleeve for locking said rod in position, substantially as and for the purpose set forth.

2. In a gas lamp, the combination of a 50 chimney having an outwardly and downwardly projecting flange at its lower end; a plurality of burners arranged in an inverted position through said flange; inverted mantles for said burners; a plate-like mantle holder having openings therethrough to receive the mantles and adapted to fit said flange on said chimney and substantially close the same, whereby the air is drawn toward the mantles by the draft of the chimney; a revolvably and vertically adjustable 55

60 mantles for said burners; a plate-like mantle holder having openings therethrough to receive the mantles and adapted to fit said flange on said chimney and substantially close the same, whereby the air is drawn toward the mantles by the draft of the chimney; an upwardly projecting supporting rod for said holder adjustably arranged through said flange on said chimney; a locking sleeve having a longitudinal slot 65 therein arranged on said rod; and a laterally projecting pin on said rod adapted to be engaged by said locking sleeve for locking said rod in position, substantially as and for the purpose set forth. 70

3. In a gas lamp, the combination of a 75 chimney having an outwardly and downwardly projecting flange at its lower end; a plurality of burners arranged in an inverted position through said flange; inverted mantles for said burners; a plate-like mantle holder having openings therethrough to receive the mantles and adapted to fit said flange on said chimney and substantially close the same, whereby the air is drawn toward the mantles by the draft of the chimney; an upwardly projecting supporting rod for said holder adjustably arranged through said flange on said chimney; a stop for limiting the upward movement of said rod; and means for locking said rod in its elevated position, substantially as and for the purpose set forth. 80

4. In a gas lamp, the combination of a 85 chimney having an outwardly and downwardly projecting flange at its lower end; a plurality of burners arranged in an inverted position through said flange; inverted mantles for said burners; a plate-like mantle holder having openings therethrough to receive the mantles and adapted to fit said flange on said chimney and substantially close the same, whereby the air is drawn toward the mantles by the draft of the chimney; an upwardly projecting supporting rod for said holder adjustably arranged through said flange on said chimney; a stop for limiting the upward movement of said rod; and means for locking said rod in its elevated position, substantially as and for the purpose set forth. 90

5. In a gas lamp, the combination of a 95 chimney having an outwardly and downwardly projecting flange at its lower end; a plurality of burners arranged in an inverted position through said flange; inverted mantles for said burners; a plate-like mantle holder having openings therethrough to receive the mantles and adapted to fit said flange on said chimney and substantially close the same, whereby the air is drawn toward the mantles by the draft of the chimney; a revolvably and vertically adjustable 100

105 supporting rod secured to said holder at one side thereof; a stop for limiting the upward movement of said rod; and means for securing the same in its elevated position, for the purpose specified. 115

6. In a gas lamp, the combination of a chimney having an outwardly and downwardly projecting flange at its lower end; a plurality of burners arranged in an inverted position through said flange; inverted mantles for said burners; a plate-like mantle holder having openings therethrough to receive the mantles and adapted to fit said flange on said chimney and substantially close the same, whereby the air is drawn toward the mantles by the draft of the chimney; and a revolubly and vertically adjustable supporting rod secured to said holder at one side thereof, for the purpose specified.
7. In a gas lamp, the combination of a plurality of burners arranged in an inverted position; a plate-like mantle holder having openings therethrough adapted to receive the mantles; a revolubly and vertically adjustable supporting rod secured to said holder at one side thereof; a stop limiting the upward movement of said rod; means for securing the same in its elevated position and means for revolubly supporting said rod in its lowered position, for the purpose specified.
8. In a gas lamp, the combination of a plurality of burners arranged in an inverted position; a plate-like mantle holder having openings therethrough adapted to receive the mantles; a revolubly and vertically adjustable supporting rod secured to said holder at one side thereof; means for securing the same in its elevated position and means for revolubly supporting said rod in its lowered position, for the purpose specified.
9. In a gas lamp, the combination of a burner arranged in an inverted position; a mantle holder; a revolubly and vertically adjustable supporting rod secured to said holder at one side thereof; a stop for limiting the upward movement of said rod; means for securing the same in its elevated position and means for revolubly supporting said rod in its lowered position, for the purpose specified.
10. In a gas lamp, the combination of a burner arranged in an inverted position; a mantle holder; a revolubly and vertically adjustable supporting rod secured to said holder at one side thereof; means for securing the same in its elevated position and means for revolubly supporting said rod in its lowered position, for the purpose specified.
11. In a gas lamp, the combination of a plurality of burners arranged in an inverted position; a plate-like mantle holder having openings therethrough adapted to receive the mantles; an upwardly projecting supporting rod for said holder; a stop for limiting the upward movement of said rod; a locking sleeve having a longitudinal slot therein arranged in said rod, the upper end of said sleeve being cam shaped; and a laterally projecting pin on said rod adapted to be engaged by said locking sleeve for locking said rod in position said pin being adapted to revolubly support said rod in its lowered position, substantially as described.
12. In a gas lamp, the combination of a plurality of burners arranged in an inverted position; a plate-like mantle holder having openings therethrough adapted to receive the mantles; an upwardly projecting supporting rod for said holder; a locking sleeve having a longitudinal slot therein arranged in said rod; and a laterally projecting pin on said rod adapted to be engaged by said locking sleeve for locking said rod in position said pin being adapted to revolubly support said rod in its lowered position, substantially as described.
13. In a gas lamp, the combination of a burner arranged in an inverted position; a mantle holder; supporting rod for said holder; a stop for limiting the upward movement of said rod; a locking sleeve having a longitudinal slot therein arranged on said rod, the upper end of said sleeve being cam shaped; and a laterally projecting pin on said rod adapted to be engaged by said locking sleeve for locking said rod in position said pin being adapted to revolubly support said rod in its lowered position, for the purpose specified.
14. In a gas lamp, the combination of a burner arranged in an inverted position; a mantle holder; supporting rod for said holder; a locking sleeve having a longitudinal slot therein arranged on said rod; and a laterally projecting pin on said rod adapted to be engaged by said locking sleeve for locking said rod in position, said pin being adapted to revolubly support said rod in its lowered position, for the purpose specified.
15. In a gas lamp, the combination of a chimney having an outwardly and downwardly projecting flange; a burner arranged in an inverted substantially vertical position through said flange; an inverted mantle for said burner; a plate-like mantle holder having an opening therein adapted to receive the mantle fitted into said flange on said chimney, whereby the air is drawn toward the mantles by the draft of the chimney, for the purpose specified.
16. In a gas lamp, the combination of a chimney having an outwardly and downwardly projecting flange at its lower end; an inverted substantially vertical burner arranged through said flange; and a plate-like mantle holder of non-heat-conducting material having an opening therethrough adapted to receive the mantle fitted into said flange whereby the air is drawn toward the mantles by the draft of the chimney, for the purpose specified.
17. In a gas lamp, the combination of a plurality of burners arranged in an inverted position; a plate-like mantle holder having

openings therein, through which said burners are arranged so that their tips are below said plate when said plate is in its operative position, said openings being adapted to receive the mantels; and a vertically adjustable support for said plate adapted, when in its lowered position, to rotatably support said plate whereby it may be swung to one side as desired, for the purpose specified.

In witness whereof, we have hereunto set to our hands and seals in the presence of two witnesses.
